UNITED STATES PATENT OFFICE.

JOHN MURPHY, OF HARTFORD CITY, INDIANA, ASSIGNOR TO WINDOW GLASS MACHINE COMPANY, OF PITTSBURGH, PENNSYLVANIA, A CORPORATION OF NEW JERSEY.

SPLITTING-BUCK FOR GLASS CYLINDERS.

1,307,209.

Specification of Letters Patent. Patented June 17, 1919.

Application filed May 10, 1918. Serial No. 233,687.

To all whom it may concern:

Be it known that I, JOHN MURPHY, a citizen of the United States, residing at Hartford City, in the county of Blackford and

5 State of Indiana, have invented a new and useful Improvement in Splitting-Bucks for Glass Cylinders, of which the following is a full, clear, and exact description, reference being had to the accompanying drawings, 10 forming part of this specification, in which—

Figure 1 is an end elevation of a splitting buck embodying my invention, and

Fig. 2 is a sectional elevation of the same.

15 My invention has relation to splitting bucks for use in splitting glass cylinders or rollers in the manufacture of glass sheets.

The object of my invention is to provide a simple and convenient form of buck upon 20 which the cylinders or rollers can be placed preparatory to splitting without danger of breaking them, and which has means for facilitating turning of the cylinders or rollers to bring them to the most advantageous splitting position.

25 The nature of my invention will be best understood by reference to the accompanying drawings, in which I have shown a preferred embodiment thereof, and which will now be described, it being premised, however, that various changes can be made in the details of construction, arrangement and combination of the several parts, without departing from the spirit and scope of my invention, as defined in the appended claims.

30 In the drawings, the numeral 2 designates suitable standards or uprights which are arranged in pairs, three of such pairs being shown. They are spaced from each other and are connected in any suitable manner so 40 as to form a rigid buck frame. The opposite standards or uprights are connected at their upper portions by flexible strips 3 of some suitable material, such as cotton belting, or canvas, these strips forming a cradle-like support for the glass cylinders or rollers when placed on the buck.

45 At each end of the buck, I provide a pair of antifriction wheels or rollers 4, which are mounted on opposite end portions of a bar 5 secured to a vertical member 6, which is mounted to slide vertically in a guide 7 attached to the buck frame. The two vertical members 6, at opposite ends of the buck, are rigidly connected by a bar 8. This bar 5 is connected by links 9 with a treadle shaft

10 journaled in the lower portion of the buck frame and having a treadle lever 11 fulcrumed at 12.

In the use of the buck, the wheels 4 are normally in the lowered positions shown in 60 the drawing, their upper edges being below the flexible supporting belts 3. The cylinder or roller to be split is laid on the buck with the parts in this position. Preparatory to splitting, it is necessary for the 65 splitter to examine the cylinder for defects, and to turn it to a position where the line of greatest defects is close to the line of split, in order to reduce waste in subsequent cutting. Heretofore, this has been done by 70 manually lifting one end of the cylinder and turning it while it is supported on the splitting buck at its opposite end. This is somewhat difficult, especially with large cylinders. In accordance with my invention, 75 the splitter simply actuates the treadle to raise the bar 8 and thereby the wheels 4, thus bringing the latter into contact with the cylinder or roller and raising it off from the belts. The cylinder can now be turned, 80 by a slight pressure of the fingers; and can be readily examined and brought to the most advantageous splitting position. The cylinder is then lowered onto the flexible supports and is split in the usual manner. 85 If the cylinder is to be again split, the wheels or rollers are again elevated and the cylinder turned thereon to a new splitting position.

The advantages of my invention will be 90 apparent since it provides a splitting buck having two sets of supports, one of a flexible and yielding character for receiving cylinders when placed on the buck, and for supporting them while splitting, and the 95 other for carrying them while being inspected and turned to proper splitting position. In this manner the operations are greatly facilitated. The wheels or rollers can be made of any suitable material, such 100 as wood.

I claim:

1. A splitting buck for glass cylinders, comprising flexible supporting means for the cylinders while being split, other vertically movable supporting means upon which the cylinders may be supported and freely rotated preliminary to splitting, said other supporting means terminating at substantially the points where they contact with the 110

cylinder when in cylinder engaging position, and means located at one end portion of the buck whereby the last named supporting means may be moved into and out of cylinder-engaging position, substantially as described.

2. A splitting buck for glass cylinders, comprising flexible supporting means for the cylinders while being split, other vertically movable supporting means upon which the cylinders may be supported and freely rotated preliminary to splitting, a foot treadle at one end of the buck extending in the direction of the length of the buck, and actuating connections between said treadle and the movable supporting means, said treadle and connections enabling the splitter to manipulate said support while turn-

ing the cylinder with the hands, substantially as described.

3. A splitting buck for glass cylinders, comprising a frame having transversely extending flexible supporting means for the cylinders while being split, a plurality of sliding members mounted on said frame, a pair of wheels journaled on each of said members, connections between said members, and an actuating device for simultaneously raising and lowering said members from the position below the plane of the flexible supporting means to a cylinder engaging position above said plane; substantially as described.

In testimony whereof, I have hereunto set my hand.

JOHN MURPHY.
